UNITED STATES PATENT OFFICE.

EDWIN E. ANGELL, OF SOMERVILLE, MASSACHUSETTS, ASSIGNOR TO THE AMERICAN SHOE MACHINERY COMPANY, OF PORTLAND, MAINE, A CORPORATION OF MAINE.

SOLE-TRIMMING MACHINE.

SPECIFICATION forming part of Letters Patent No. 688,815, dated December 17, 1901.

Application filed February 23, 1899. Serial No. 706,561. (No model.)

To all whom it may concern:

Be it known that I, EDWIN E. ANGELL, of Somerville, in the county of Middlesex and State of Massachusetts, have invented certain new and useful Improvements in Boot or Shoe Trimming Machines, of which the following is a specification.

This invention relates to machines especially adapted for trimming and randing the soles of boots and shoes, and especially adapted for "rough-rounding" and randing the heel-seats of boots and shoes, by which is meant trimming off the surplus stock of the sole around the heel, and by "randing" is meant trimming the upper edge between the upper side of the sole and the counter of the heel or between the sole and the upper.

My invention consists of certain novel features hereinafter described, and particularly pointed out in the claims.

In the accompanying drawings, which illustrate a construction embodying my invention, Figure 1 is a front view of a portion of a boot and shoe trimming machine. Fig. 2 is a view of the lower part of the machine with the lower part of the base in section. Fig. 3 is a side view of a portion of the sole-guard and carrier in section. Fig. 4 is a perspective view of the sole-guard carrier. Fig. 5 is a perspective view of the bell-crank lever hereinafter described. Fig. 6 is a sectional view of the front end of the carrier-spindle. Fig. 7 is a side view of the improved sole-guard and holder. Fig. 8 is a top plan view of the sole-guard. Fig. 9 is a plan view of the sole-guard and adjustable ring. Fig. 10 is a cross-sectional view through the sole-guard. Fig. 11 is a cross-sectional view through the adjustable ring. Fig. 12 is a plan view of the sole-guard and sole-guard holder. Fig. 13 is a top plan view of the machine, showing my improvements applied thereto.

Like letters of reference refer to like parts throughout the several views.

A represents a yoke-shaped casting provided with two arms A', which carry at their upper ends the bearings B for the cutter-shaft A². The carrier C is provided with a hub C', around which is located the sole-guard holder D, and which on the extreme ends of the arms

D² is provided with a screw-thread D', on which is secured the adjustable ring E, provided on its outside surface with the recess E', in which the lip F' of the sole-guard F rests and upon the ring E the sole-guard F revolves. 55 The sole-guard holder D is secured to the sole-guard carrier by a set-screw A⁴, and the adjustable ring E is secured in its adjusted position by the set-screw D³. The sole-guard F is corrugated on its outer surface, as shown at F², for 60 the purpose of providing a roughened surface in order to grip the leather in the operation of the machine. The lip F' prevents the sole-guard from being moved off of the ring E and also prevents the dirt from working into 65 the bearings. This lip is formed after the sole-guard F has been placed on the ring E, and said lip is formed by rolling the lower part of the sole-guard into the annular recess E' of the ring E. The sole-guard is made ro- 70 tatable in order to move with the work as the work moves around the cutter, and thereby reduces the friction over a construction in which the sole-guard is made permanent, and, further, it is obvious that by being ro- 75 tary the labor of the operator is reduced. Oil is applied for lubricating by dropping it into the recess E', and from said recess the oil works out through the slots E², which lead from said recess E', and lubricates the sole- 80 guard.

Loosely mounted on the shaft A² is an extension-blade holder G, provided at its forward end with the blades G', which feather-edge the bottom of the sole. On the rear end 85 of the extension-blade holder is the threaded nut H, which is screwed upon the blade-holder up to its shoulder H' and holds the said holder with relation to the sole-guard carrier C. In the sole-guard carrier C is mounted the hol- 90 low screw I, which is mounted upon the carrier-spindle J, which extends rearwardly, and around its center is provided the spring K, which bears against the forward end of the spindle J at K' and at its rear end bears 95 against the casting at K², and the object of said spring is to throw forward the sole-guard carrier and connecting parts which automatically provides proper pressure for the sole-guard against the work. The spindle J passes 100

rearwardly through the fork L of the bell-crank lever L', which is pivoted at L² to the holder L³, said holder L³ being secured in its adjusted position by the set-screw L⁴. To the 5 lower end of the bell-crank lever at L⁵ is connected the rod L⁶, which extends downwardly and is connected to an arm M, fast on the shaft M'. The yoke N has at its lower end the 10 guide-pin N', which, as shown, is located in the hole N² in the casting for the purpose of guiding and preventing the spindle J from turning around while the sole-guard carrier is being adjusted by means of the screw I, the screw I being secured firmly in its adjusted position 15 by the set-screw J', screwing into the opening J² of the spindle J. The yoke N is secured to the spindle J by means of the pin N³ to hold them rigid to one another. On the extreme 20 lower end of the sole-guard carrier is mounted a guide-stud C², which moves in the yoke-east- 25 ing A for the purpose of holding the carrier C in its proper working position. On the rock- shaft M' is fixed fast a treadle M², and upon movement being imparted thereto by the foot 30 of the operator the spring O, which is attached to the arm M at one end and at its other end to any desirable part of the base, yields to the movement of said rock-shaft. By means of the treadle M², rod L⁶, bell-crank lever L', and 35 spindle J the sole-guard carrier C and sole- guard F are moved rearwardly for the introduction of the work to the cutters, which in practice are mounted upon the tapered end A³ of the cutter-shaft A² in the manner illustrated in United States Patent to Vose, No. 560,825, dated May 26, 1896, and, as shown in Fig. 13, the cutter A⁵ is mounted on the tapered end A³ of the shaft A², and over said cutter is located the cutter-guard A⁶, mounted on the 40 hub A⁷, carried by the movable arm A⁸, and said guard is capable of being removed from proximity to the cutter A⁵ when it is desired to gain access to said cutter. Upon the removal of the foot the sole-guard is pressed 45 forward by the spring J in contact with the sole, and the sole is held in its proper working position between the sole-guard, cutter, and cutter-shield. The sole-guard F being mounted as described revolves with the work 50 when it is being acted on by the cutters, there-

by preventing injury to the work. The hollow screw I is for the purpose of regulating the pressure of the spring K for the adjustment of different variations of thickness of soles, so that by this arrangement the same pressure 55 may be obtained for thick soles as for thin soles.

I do not claim in this application the construction of the extension-blade holder, as the same forms the subject-matter of another application filed by me simultaneously herewith and having the serial number 706,563.

I do not limit myself to the arrangement and construction shown, as the same may be varied without departing from the spirit of 65 my invention.

Having thus ascertained the nature of my invention and set forth a construction embodying the same, what I claim as new, and desire to secure by Letters Patent of the 70 United States, is—

1. In a boot and shoe trimming machine, a sole-guard carrier, a sole-guard holder on said carrier, an adjustable ring on said holder, and a sole-guard movably mounted on said ring 75 and adapted to move with the work in the operation of the machine.

2. In a boot and shoe trimming machine, a sole-guard carrier, a sole-guard holder on said carrier, an adjustable ring on said holder, and 80 a sole-guard having an inwardly-turned lip on its inner edge adapted to fit into said recess on said ring and movably mounted on said ring and adapted to move with the work in the operation of the machine.

3. In a boot and shoe trimming machine, a carrier provided with a hub, a holder mounted on said hub, a ring adjustable on said holder and provided with an annular recess, a sole- 85 guard rotatable on said ring and having an annular lip bent into said recess for holding said guard in place.

In testimony whereof I have signed my name to this specification, in the presence of two subscribing witnesses, this 15th day of 90 February, A. D. 1899.

EDWIN E. ANGELL.
